FIG. 1.

FIG. 2.

FIG. 5.

FIG. 3.

Inventor
Rolland T. R. Hastings
By Cigar Co. Atty.

UNITED STATES PATENT OFFICE.

ROLLAND T. R. HASTINGS, OF HIGHLAND PARK, ILLINOIS, ASSIGNOR TO SANITAX BRUSH COMPANY, OF CHICAGO, ILLINOIS, A CORPORATION OF ILLINOIS.

BRUSH.

Application filed March 25, 1922. Serial No. 546,580.

To all whom it may concern:

Be it known that I, ROLLAND T. R. HASTINGS, a citizen of the United States, residing at Highland Park, in the county of 5 Lake and State of Illinois, have invented new and useful Improvements in Brushes, of which the following is a specification.

This invention relates to means for fastening tufts of bristles in brushes and more 10 particularly to brushes of that type having bristle holders provided with a plurality of nipples forming sockets in which the bristle tufts are secured.

One object of my invention is to secure or 15 fasten each tuft of bristles in the bristle holder by a staple having its prongs clinched against the back of the holder, thus providing a separate fastener for each tuft of bristles and avoiding a continuous and un- 20 broken fastening wire as heretofore employed in brushes of this general type, with the result that the bristles may be secured more tightly in the holder and fastened with much ease and dispatch than with the 25 single wire as heretofore.

Another object of my invention is to direct the pointed ends of the staple prongs, on being clinched, against the back of the bristle holder and into the material of the 30 holder so as to secure not only an anchorage for the clinched ends of the staples to hold them against lateral movement, but also to effect a tight drawing action on the bristle tufts into the nipples or sockets in which 35 they are secured, and thus hold the bristles tightly in place.

The invention consists further in the mat- 40 ters hereinafter described and more particu- larly set forth in the appended claims.

40 In the accompanying drawings

Figure 1 is a top plan view of a brush embodying the features of my invention;

Fig. 2 is an enlarged fragmentary top plan view of one of the longitudinal bars of the 45 bristle holder of the brush;

Fig. 3 is a longitudinal vertical sectional view taken on line 3-3 of Fig. 2; and

Figs. 4 and 5 are transverse vertical sec- 50 tional views taken on lines 4-4 and 5-5, respectively, of Fig. 3.

The brush shown in the drawings has a back in the form of an open frame 1, from one end of which projects a handle 2. The latter is in the plane of the back and is 55 preferably made integral therewith by cast-

ing or otherwise. The brush has a bristle holder 3. This is preferably made of metal, like the frame and handle, and has the same general shape as the frame 1 to fit in the same from the under side thereof. Said 60 holder 3 is held in the frame 1 along the marginal portions of the parts and is pro- vided with a plurality of rows of slots 4, which form between them bars 5 in which the tufts of bristles 6, 6 are secured in ac- 65 cordance with my invention. Each bar 5 has a row of depending nipples 7 forming sockets to receive the tufts of bristles 6. The back 1 being in the form of an open frame, and the bristle holder 3 being slotted, 70 allows holding the brush under a faucet and running water through the brush for cleansing the bristles and keeping the brush clean and sanitary.

For securing the tufts of bristles 6 in the 75 sockets formed by the nipples 7, 7, I pro- vide for each tuft of bristles a securing mem- ber in the form of a staple 8. As shown in the drawings, each tuft of bristles is doubled on itself to form a loop 9 at the folded end 80 of the tuft. The looped portion 10 of the staple 8 is engaged with the loop 9 in the bristle tuft and both are inserted into a nipple 7 with the prongs 11, 11 of the staple 85 projecting beyond the bristle tuft. Each bar 5 has a plurality of apertures or holes 12, 12, one for each of the nipples 7 on the bar 5. Each aperture 12 opens at its lower end into its associated nipple 7 and at its upper end into a groove 13 in the upper sur- 90 face of the bar 5 and common to all of the nipples on said bar.

In inserting each staple 8 into a nipple 7, its prongs 11 are passed through the aperture 12 of that nipple and project into and 95 above the groove 13. The upper ends of the prongs 11, 11 are then bent or clinched against the bottom of the groove 13 on oppo- site sides of the aperture 12. In clinching 100 the prongs, the pointed ends thereof are di- rected downward against the bottom of the groove 13 and are impinged or embedded in the metal of the bristle holder, as shown in Figs. 3 and 5.

The pointed ends of the prongs 11, 11 be- 105 ing in contact with the bars 5 on opposite sides of the apertures 12 and curved down- ward into engagement with the bars, as shown, causes the bristle tufts 6 to be held tightly in the nipples 7 because the bending 110

of the prongs downward into engagement with the bars prevents downward movement of the staples 8 to loosen the bristle tufts engaged thereby. Also the staples 8 holding the folded portions 9 of the bristle tufts 6 tightly against the ends of the nipple sockets holds the staples against upward movement and this is further guarded against by reason of the fact that the looped portions 10 of the staples in securing the bristle tufts in place are widened out to an extent greater than the apertures 12, as shown in Fig. 4.

By the construction described, there is a separate fastener for each of the bristle tufts 15 6; thus avoiding the use of a continuous and unbroken wire engaging all of the bristle tufts distributed over the entire surface of the bristle holder as heretofore. This is an advantage in that the fastening of the bristle tufts in the nipples may be facilitated by requiring only the tightening of each fastener in place, and the tightening effect of one fastener is not dependent on the tension put on another as with a continuous strand 20 of wire as heretofore.

Moreover, by having a separate fastener for each bristle tuft, the variation in the material may be readily compensated for by tightening the particular fastener. Then 30 again, the fact that the pointed ends of the staple prongs 11 are impinged against or embedded in the metal of the bristle holder prevents the staples from creeping while the brush is in use and thus holds the bristles 35 tightly in place. Moreover, the prongs of the staples being turned down toward the body of the brush holder effects a tight fastening of the bristles in place as heretofore mentioned. Also the pointed ends of the prongs 40 being embedded in the metal of the bristle holder prevents the possibility of the prongs projecting beyond the bristle holder to scratch the hand or catch in the clothing of the user of the brush.

45 After the bristle tufts 6, 6 are anchored or fastened in the nipples 7, 7 by the staples 8, 8, the outer ends 14 of the nipples are bent or swaged inward against the bristles, as shown in the drawings and more particularly in Figs. 3 and 4 thereof. This aids in clamping the bristles in the nipples 7 and thus co-operates with the staples 8 in securing the bristles tightly in place. The outer end of the left-hand nipple 7 in Fig. 3 is 55 shown in dotted lines 15 before being bent inward against the tuft of bristles in that nipple.

I claim as my invention:

60 1. A bristle holder, comprising a body portion having bristle receiving sockets, said holder having apertures extending therethrough into said sockets, folded tufts of

bristles in said sockets, and a separate staple for fastening each bristle tuft in its socket, said staples engaging the folded portions 65 of the bristle tufts and having their prongs extending through said apertures, the prongs of said staples being clinched against the side of the holder opposite said sockets and having their pointed ends embedded in the 70 same on opposite sides of said apertures.

2. A bristle holder, comprising a body portion having bristle receiving sockets on its under side, said holder having apertures 75 extending therethrough into said sockets, folded tufts of bristles in said sockets, and a separate staple for fastening each bristle tuft in its socket, said staples engaging the folded portions of the bristle tufts and having their prongs extending 80 through said apertures above the upper side of said holder, the prongs of said staples being clinched against the upper side of said holder by being curved downward toward the same and having their pointed ends embedded 85 therein on opposite sides of said apertures.

3. A bristle holder, comprising a body portion having bristle receiving sockets on its under side and arranged in rows, said 90 holder having grooves in its upper side above said rows of sockets, said holder having apertures extending therethrough and opening into said grooves and sockets, respectively, folded bristle tufts in said sockets, 95 and a separate staple for fastening each bristle tuft into its socket, said staples engaging the folded portions of the bristle tufts and having their prongs extending through said apertures into said grooves, the 100 prongs of said staples being clinched against the bottoms of said grooves and having their pointed ends embedded in the holder on opposite sides of said apertures.

4. A bristle holder, comprising a slotted body portion having connected bars, each bar having a row of nipples on its under side, each bar having a groove in its upper side above the nipples thereon, said bars being provided with apertures opening into 110 said grooves and nipples, respectively, folded tufts of bristles in said nipples, and a separate staple for fastening each bristle tuft in its nipple, said staples engaging the folded portions of the bristle tufts and having their prongs extending through said apertures, the prongs of said staples being clinched against the bottoms of said grooves 115 and having their ends embedded in the same on opposite sides of said apertures.

In testimony that I claim the foregoing as my invention, I affix my signature this 3rd day of March, A. D. 1922.

R. T. R. HASTINGS.
